DESIGN FOR A COMBINATION LAMP AND PICTURE DISPLAY

Alfred Aichele, Edgewood, R. I.

Application April 27, 1934, Serial No. 51,564

Term of patent 14 years

To all whom it may concern:

Be it known that I, ALFRED AICHELE, a citizen of Germany, residing in Edgewood, county of Providence, State of Rhode Island, have invented a new, original, and ornamental Design for a Combination Lamp and Picture Display, of which the following is a specification, reference being had to the accompanying drawing, forming a part thereof.

Figure 1 is a perspective view of a combination lamp and picture display, showing my new design; and Figure 2 is a sectional view on line 2—2 of Fig. 1, of the same.

I claim:

The ornamental design for a combination lamp and picture display as shown.

ALFRED AICHELE.
